UNITED STATES PATENT OFFICE.

CHARLES FISHER, OF CHICAGO, ILLINOIS, ASSIGNOR OF ONE-THIRD TO ALBERT C. GRUNWALD, ONE-THIRD TO CARL E. CARLSON, AND ONE-THIRD TO FRED H. LOESCHER, ALL OF CHICAGO, ILLINOIS.

TOILET-PAPER PACKAGE.

Application filed September 18, 1920. Serial No. 411,235.

To all whom it may concern:

Be it known that I, CHARLES FISHER, a citizen of the United States, residing at 3100 Carroll Ave., Chicago, in the county of Cook and State of Illinois, have invented a new and useful Improvement in Toilet-Paper Packages, of which the following is a specification.

This invention relates particularly to a package of toilet-paper adapted to be introduced into a service cabinet and caused to engage a supporting member, preferably in the form of a plate provided with a retaining shoulder. Such a package of toilet-paper is adapted for use, for example, in a service cabinet of the construction set forth in my application No. 411,236 filed in the United States Patent Office on even date herewith. The cabinet is provided with serving mechanism adapted to feed the sheets downwardly, seriatim, this mechanism operating to split the paper engaged by the supporting plate as the sheets are successively drawn downwardly in operation of serving them from the cabinet.

The primary object of the present invention is to provide a package of toilet-paper which can be easily introduced into operative position in such cabinet. Another object is to provide for the manufacture of such packages in an inexpensive manner. An additional object is to provide packages of this character which can be packed conveniently and kept in perfect form, thus facilitating their introduction into the cabinet and insuring the proper operation of the cabinet.

The invention is illustrated in the accompanying drawing, in which—

Fig. 1 represents a broken vertical sectional view of a package of toilet-paper showing the same applied to the supporting blade of a cabinet;

Fig. 2 a similar view illustrating the manner in which the package is applied to the supporting blade;

Fig. 3, a plan sectional view of the package;

Fig. 4, a view of a blank from which a package fastener is made;

Fig. 5 a view of the package fastener formed therefrom; and Fig. 6 a broken rear elevational view of the package.

In the illustration given, A represents a

supporting blade or hook of a cabinet; B, a package of toilet-paper; and C, a package-fastener, or clip, employed.

The package B comprises a suitable number of strips or sheets 1 of tissue paper. The package is provided near its upper edge 60 with a slit, or thin perforation, or slot 2, which is centrally located near the upper edge of the package.

The fastener or clip C is preferably formed from a strip of flexible resilient 65 paper, shown in Fig. 4. This strip is designated 3. The preferred manner of forming the clip is to fold the strip 3 on the central line 3^a, and then punch the folded member in such manner as to leave a head portion 3^b 70 and arms 3^c. The arms 3^c are rounded or tapered at their extremities as indicated at 3^d.

In the manufacture of the package, the slit 2 is formed by forcing a pointed blade through the package of paper; and the arms 75 3^c of clip are then inserted through the slit. The extremities 3^d of the arms are then bent in opposite directions, and the head portion 3^b of clip is folded over against the opposite side of the package, as indicated in 80 Fig. 3. Thus, the plies of paper which form the arms 3^c serve to line the sides of the slit, and the space between these plies serves as a channel or guide to permit the entry of the blade A without disarrangement of the 85 sheets of tissue paper. When the blade is entered, it serves to extend the head portion 3^b of the clip at right angles to the plane of the package, and the clip may then be withdrawn from the package, leaving the package 90 engaged by the hook or shoulder of the support A.

It should be noted from Fig. 5 that the offset forming the head 3^b is an edgewise offset which affords an edge-like shoulder 95 adapted to engage the front surface of the package of paper; and it will be understood from Fig. 1 that the slit 2 lies in a vertical plane perpendicular to the front face of the package. It follows that the members 3^c of 100 the fastener, while horizontally disposed, lie in a vertical plane. The surfaces of the fastener which contact with the fastener are ungummed, so that the fastener, as shown in Fig. 2, can be freely withdrawn from the slit, leaving the package impaled on the blade as illustrated in Fig. 1. Thus the sheets of toilet paper may be readily rup-

tured or slitted from the slit 2 to the upper edge when the sheet is drawn downwardly to effect its discharge from the cabinet.

In Fig. 3, the arms 3^c are shown separated, or with a space between them, such as would be caused by the entry of the blade A. In practice, the plies 3^c lie closely adjacent each other until the blade is inserted, and thus form a lining for the slit, permitting easy insertion of the blade.

The packages of paper, bound at one end by the fasteners or clips C, may be packed conveniently in a box or large package; and the individual packages may be taken and introduced into the cabinet as required. It is highly important to the successful operation of the cabinet, that the tissue paper of the package should not be disarranged; also, it is important that the package be such as to enable it to be easily and properly introduced into the cabinet.

The package described may be cheaply manufactured, and enables the above objects to be attained.

The foregoing detailed description has been given for clearness of understanding only, and no unnecessary limitation should be understood therefrom, but the appended claims should be construed as broadly as permissible in view of the prior art.

What I regard as new, and desire to secure by Letters Patent, is:

1. As an article of manufacture, a package of toilet-paper sheets having a longitudinal slit extending therethrough near one end of the pack, and a fastener comprising a paper strip folded at an intermediate transverse line and having an edge-wise offset

head portion affording a shoulder, the members of the folded strip extending through and lining said slit and having their extremities bent, thus affording a guide adapted to permit the entry of a supporting blade when the package is introduced into a service cabinet.

2. As an article of manufacture, a package of toilet-paper sheets having a longitudinal slit extending therethrough near one end of the pack, and a fastener comprising a flexible member having a shoulder engaging one side of the package and having members extending through the slit and lining the side walls thereof, thus affording a guide adapted to permit the entry of a supporting blade when the package is introduced into a service cabinet, said fastener having ungummed surfaces adjacent the package of paper and being capable of being freely withdrawn after the entry of said blade in said slit.

3. As an article of manufacture, a package of paper sheets having a longitudinal slit therethrough near one end, and a fastener comprising a paper strip folded at the center of its length to provide two arms which line the slit, said fastener having its folded end portion enlarged to provide a head engaging one side of the package and having the extremities of its arms folded in opposite directions against the other side of the package, said fastener being without gummed connection with the package and capable of being freely withdrawn after the package has been impaled on a supporting blade in a cabinet.

CHARLES FISHER.
